UNITED STATES PATENT OFFICE.

JEROME C. TAFT, OF PROVIDENCE, RHODE ISLAND.

SEWING-MACHINE.

SPECIFICATION forming part of Letters Patent No. 547,867, dated October 15, 1895.

Application filed February 16, 1895. Serial No. 538,670. (No model.)

To all whom it may concern:

Be it known that I, JEROME C. TAFT, a citizen of the United States, residing at Providence, in the State of Rhode Island, have invented a new and useful Improvement in Sewing-Machines, of which the following is a specification.

My invention relates to a sewing-machine in which the needle is alternately passed through the fabric and over the edge of the same, whereby the needle-loop of each alternate stitch will be drawn across the said edge; and it consists in the improved construction of the looper-arms for the employment of two threads in the stitch and in the improved combination of the needle and the looper-arms with means for changing the position of the stitch in the fabric and in certain details of construction, as hereinafter fully set forth.

In the accompanying drawings, Figure 1 represents a side elevation of the machine with the needle at its inward position. Fig. 2 represents a front elevation. Fig. 3 represents a rear elevation, partly in section. Fig. 4 represents a section taken in the line 4-4 of Fig. 5. Fig. 5 represents a top view of the carriage with the upper portion of the machine removed, showing the looper-arms at their extreme forward position. Fig. 6 represents a similar view with the looper-arms at their rearward position. Fig. 7 represents a side elevation with the needle in its outward position. Figs. 8 to 15 are detail views of the looper-arms. Figs. 16 and 17 are sections showing the construction of the frictional device for preventing the improper forward movement of the machine along the track. Figs. 18 and 19 are perspective views illustrating the formation of the stitch.

In the accompanying drawings, A represents the supporting-track upon which the machine moves, and B the carriage, which is supported for movement along the track by means of the flanged wheels C C C C, which wheels are held loosely upon the fixed axles D D', and to the carriage B is secured the under plate E, provided at its corners with the ears F F F F, which extend downward below the level of the under surface of the track A, and are provided with the antifriction-rollers C' C', which bear against the under surface of the track A in opposition to the flanged wheels

C C above the said track. The under plate E is connected to the carriage B and adapted to transmit a yielding pressure to the track by means of the upright studs G G, attached 55 to the plate E and passing loosely through the perforations a in the carriage B, and which are provided at the upper side of the carriage B with the springs b held upon the studs G by means of the collets c. Upon the stationary axle D is loosely held the ratchet-wheel I, and loosely upon the loose collar i' upon the said axle, at the side of the ratchet-wheel, is placed the vibrating arm J, to the side of 60 which is pivoted the pawl K, which engages with the teeth of the ratchet-wheel I; and operative connection is made from the vibrating arm J to the eccentric L upon the cam-shaft M by means of the connecting-rod N, the said 65 connecting-rod being pivoted to the adjustable piece N', secured to the side of the arm J.

To the side of the loose ratchet-wheel I is secured the gear D², which is also secured to the adjacent side of the flanged wheel C, so 70 that the said ratchet-wheel, gear, and flanged wheel will be caused to move together, the gear D² being made to engage with the rack C². The end c' of the stationary axle D is slotted to receive the tightening cam-lever d' 75 and also the sliding shoe e' for the action of the said cam-lever, and loosely upon the axle D is placed the sliding flanged sleeve B², which is recessed to receive the spiral spring f' and the loose washer g', which rests against 80 the forward edge of the shoe e', and between the sliding flanged sleeve B² and the flanged wheel C is placed the yielding friction-disk h', by means of which the proper degree of 85 friction may be produced to prevent the free 90 movement of the machine when the ratchet-wheel I is not being positively acted upon by the pawl K, thus tending to hold the carriage and the attached sewing mechanism in their properly set position for making stitches of 95 uniform length in the fabric. Upon the shaft M is placed the cam O, which serves to operate the needle-arm P, which arm is pivoted to the frame at the point a' and at its lower end carries the curved needle b'. To the shaft M 100 is also secured the cam Q, which serves to impart a vibratory movement to the upright spindle R, to the lower end of which is attached the hook-formed lower looper-arm S,

and loosely upon the spindle R is placed the 5
slidable hook-formed upper arm S' of the
looper, which arm is prevented from turning
upon the spindle R by means of the down-
wardly-extending pin c', which passes loosely
through a suitable perforation c² made in the
lower looper-arm S. The hub d' of the arm
S' is provided with the flange e, and upon the
spindle R, above the hub d', is placed the
10 spiral spring f, which will serve to force the
upper arm S' down upon the lower arm S, the
said upper arm being raised against the down-
ward action of the spring f, by means of the
forked bell-crank lever T, which engages with
15 the under side of the flange e, and is operated
by the cam U upon the shaft M, and to the bell-
crank lever T is attached the guide u, which
serves to prevent the formation of a loop upon
the upper side of the needle. The hook-formed
20 lower looper-arm S is provided at its outer end
with the eye e', through which the thread a²
from the horizontal spool A² is made to pass
and also with the rear guiding-eye e² and the
open groove e³ at the under side of the hook.
25 The hook-formed upper looper-arm S' is pro-
vided with the projecting horn e⁴, which forms
the thread-receiving recess e⁵, which is adapt-
ed to hold the binding-thread a² running
from the horizontal spool A², while the threads
30 from the spools A² and A³ are being spread
for the entrance of the needle between them.
To the side of the needle-arm P is pivoted the
spring-actuated arm q, which at its lower end
embraces the needle and serves, by bearing
35 against the outer side of the fabric, to secure
the proper formation of the needle-loop when
the stitch is being taken over the edge of the
fabric and operates in this case to prevent the
backward movement of the loop with the nee-
40 dle, and a suitable stop is provided for the
arm q by means of the pin r. The fabric
guide V is provided with a dovetailed slide g,
which enters a corresponding vertical groove
h made in the side of the carriage B, whereby
45 the said guide is made capable of an up-and-
down movement, which movement is imparted
thereto by means of the arm W, the said arm
being held between the top of the slide g and the
under side of the pin i, which pin projects
50 backward from the inner side of the guide V.
The arm W is attached to the rock-shaft j,
which is held loosely in the transverse bearing k,
and to the opposite end of the said rock-
shaft is attached the cam-arm l, which en-
55 gages at its outer end with the cam X. (Shown
in dotted lines upon the inner side of the gear
Y, the said gear being held to turn loosely
upon the stud m and engaging with the teeth
of the pinion Z upon the shaft M.) To the
60 hub n of the gear Y is attached the hand-
crank o, by means of which the machine is op-
erated. The guide V for the fabric may be
preferably provided with the downwardly-
projecting blade p, which enters between the
65 edges of the two pieces of fabric which are to
be sewed. The pieces of fabric to be sewed

together edge to edge are to be suitably
stretched side by side and held by a proper
support independent of the machine, so that
the edges of the said pieces of fabric will
rest against the horizontal bearing-surfaces
s s of the guide and also have a lifting ten-
dency thereon, whereby the edges of the said
pieces will automatically follow the said guide
in its upward movement. 75

Upon turning the hand-crank o the machine
will be fed along the track intermittently by
means of the ratchet mechanism, each for-
ward movement of the machine being made
equal to the desired length of the stitch, and
as the needle-arm P is moved forward by the
action of the cam O, the threaded needle b'
will be first passed through the fabric and
then drawn back to make the loop. The
looper-arms S S' are now passed together 85
through the needle-loop, and the needle with-
drawn from the fabric, leaving its loop at the
bend a⁴ of the hooks of both looper-arms. The
fabric is now, by the downward movement of
the fabric-guide V, pressed down below the 90
penetrating plane of the needle, and the up-
per looper-arm rises from the lower looper-
arm, thus spreading the needle-loop and the
accompanying binding-thread a², which bind-
ing-thread is held in advance of the needle-
loop a³ at the forward ends of the looper-arms.
The needle now passes forward over the fabric
and through the loop of the binding-thread
a² and in advance of the needle-loop a³, as
shown in Fig. 19. The looper-arms are now 100
caused to recede and discharge the loop of the
binding-thread a² onto the needle, and re-
ceding farther the needle-loop a³ is discarded
from the looper-arms onto the loop of the
binding-thread. Now the upper looper-arm 105
closes down upon the lower looper-arm and
the needle recedes to form another loop. Then
the looper-arms come forward and pass
through the needle-loop. Then the needle re-
cedes, leaving the needle-loop upon the looper-
arm at the base a⁴ of the looper-hook. Now
the fabric is allowed to rise above the pen-
etrating line of the needle, and the upper looper-
arm is caused to rise to spread both the needle-
loop and the loop of the binding-thread a², so 115
that the needle will pass through the fabric
and through the loop of the binding-thread
a² in advance of the needle-loop. The looper-
arms now recede and discard the loop of the
binding-thread a² upon the needle, and upon 120
the further backward movement of the looper-
arms the needle-loop is discarded upon the
loop of the binding-thread a², as before; and
this operation is continuously repeated in
sewing the fabric, the operation of the needle 125
being the same whether the stitch is taken
over or through the fabric. The cam-arm l
is attached to the rock-shaft j by means of
the removable pin z³, which enters a suitably-
located perforation made in the said shaft, and
when the said cam-arm l is thus attached the 130
fabric-guide V will be so operated that each

5 alternate stitch will be taken above the fabric; but if it is desired to take the stitches uniformly through the fabric, as may be desirable in some cases, then by removing the pin 5 z^3 from the cam-arm l the said cam-arm will be rendered loose upon the shaft j , so that the cam X will not affect the fabric-guide to cause the up-and-down movement of the same, and then by inserting the pin z^3 into the perforation j^4 in the carriage B , so as to enter a corresponding hole in the shaft j , the fabric-guide V may be permanently held in an elevated position, so that the stitches will be taken uniformly through and through the fabric.

10 15 I claim as my invention—

1. In a sewing machine, the combination of the reciprocating eye pointed needle, with the lower looper-arm, provided with the thread guiding and thread delivering eyes, and the 20 intermediate groove at the under side of the looper arm, and the movable upper looper-arm, provided with the projecting horn which forms a recess for holding the thread when spreading the loop, substantially as described.

25 2. In a sewing machine, the combination with the oscillating looper arms, and the fabric guide, of the reciprocating eye pointed needle, and the spring actuated arm arranged upon the needle carrier, and having an open-

ing through which the needle passes, substantially as described. 30

3. In a sewing machine, the combination with the track provided with the rack, the carriage, the flanged wheels, the loose gear engaging with the rack, the ratchet wheel and pawl for operating the gear, and the spring actuated frictional means arranged upon the fixed axle, to prevent the improper movement of the carriage along the track, in spacing the 35 stitch substantially as described. 40

4. In a sewing machine, the combination with the stitch forming mechanism, and the carriage, the vertically moving fabric guide, and the cam for giving the fabric guide an up and down movement, of the intermediate rock-shaft and the connecting arms, and means for optionally either securing the fabric guide in an inoperative elevated position for making the stitch through and through the fabric, or securing the cam arm to the shaft, whereby an 45 up and down movement will be imparted to the fabric guide, to cause the loop of each alternate stitch to be drawn over the edge of the fabric, substantially as described. 50

JEROME C. TAFT.
